(57) **CLAIM**

The ornamental design for a two-burner stove, as shown and described.

DESCRIPTION

FIG. 1 is a front left perspective view of a two-burner stove showing our new design, the stove having a shelf beneath two exposed burners;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The details shown in broken lines in all views are for illustrative purposes only and form no part of the claimed design.
